CONTAINER FILLING AND SEALING MACHINES

Rudolph Schmidt, Scotch Plains, N.J., assignor to United Shoe Machinery Corporation, Flemington, N.J., a corporation of New Jersey

Filed July 28, 1958, Ser. No. 751,519

8 Claims. (Cl. 53—281)

This invention relates to packaging and more particularly to machinery for filling and sealing containers. The use of disposable containers holding small quantities of products which are to be consumed without the containers subsequently being resealed presents a definite advantage in convenience of handling and distribution when the protection afforded by the containers to their contents permits lengthy storage before use. For example, food products, such as jams, syrups, condiments, etc., packaged in quantities representing single servings or portions, in receptacles known as unit containers, are becoming increasingly more popular in restaurants, railroads, airlines, and the like. Since these containers most often are distributed directly to their ultimate consumers for immediate use they must be easily opened without the aid of tools, such as a conventional can opener.

For the most part, unit containers have been made of inexpensive flexible plastic material. However, a major disadvantage of a container made of this type of material is that it is susceptible to the penetration of air, and accordingly its contents, if perishable, may spoil in a relatively short time. To overcome this and therefore provide a longer shelf life, unit containers are being made of lightweight metals, such as aluminum, which, when hermetically sealed by plastic fusion with a cover of like material, afford protection to their contents for a considerably longer time and furthermore can be opened without the use of tools. Since the advantage of the system of unit portion distribution is economically predicated upon high quantity production, it is mandatory that reliable, relatively high speed machinery, both automatic and semi-automatic, be employed in the production and handling of unit containers. It is to this end that this invention is directed.

One of the objects of the present invention is to provide a machine for filling unit containers and sealing them with an easily removable cover thereby to provide an airtight package which may be opened without the aid of tools.

Another object of this invention is to provide an easily cleaned unit container filling and sealing machine which is particularly adapted to the handling of food products.

Another object of this invention is to provide a unit container filling and sealing machine in which the instrumentalities which come in contact with the container are completely separated from the driving instrumentalities.

Still another object of this invention is the provision of a unit container filling and sealing machine which has various operating instrumentalities all of which are

2

operated from self-contained hydraulic and pneumatic systems requiring no outside supply of fluid or gas.

A typical unit container is a shallow, substantially cylindrical, cup-like receptacle generally of aluminum, having a flange extending radially around the open end. The interior of the cup and the upper surface of the flange are coated with a thermoplastic material, such as vinyl. An aluminum cap or cover, which may be provided with a label, is hermetically sealed to the upper surface of the flange through fusing of the vinyl coatings on the contacting surfaces of the cover and of the flange.

In accordance with the above objects and as a feature of this invention there is provided a machine having a turret with a plurality of cavities formed to receive flanged unit containers of the type described above. The turret, which may be loaded automatically or by hand, indexes the containers to a piston-type filling machine which deposits a predetermined quantity of material in each of the containers. From the filling station, the container is indexed to mechanism which positions a cover on the flange of the filled container. Next, the covered container is sealed by mechanism which causes the contacting vinyl coated surfaces of the cover and the flange to be fused thereby producing an airtight seal. The final step is the removal of the sealed container from the turret by mechanism which elevates the containers from the cavities and displaces them onto a collecting chute or trough. The turret is indexed by a Geneva drive mechanism which is particularly designed so as not to spill the contents of the containers by the provision of means for reducing the acceleration and deceleration at the beginning and end of each indexing motion. Each of the operating instrumentalities or work stations including the filler, cover positioner, sealer and ejector, etc., are operated by individual hydraulic cylinders, the cylinders in turn being operated by master cylinders of the type commonly used to operate automobile brakes. All of the master cylinders are cam operated and are positioned within a housing or compartment separated from the operating instrumentalities. The cover positioning member is operated in part pneumatically, but does not require an outside source of vacuum or compressed air, both being provided by a single unit contained within the above-mentioned compartment and likewise operated by cam mechanism within the compartment. All of the operating instrumentalities are arranged to be readily cleaned, and constructed of non-corrosive material and positioned so that any spilled material can be readily removed, for example, by the application of pressurized steam, without disassembling the machine or its driving mechanism.

The above and other features of the invention including various novel details of construction and combinations of parts will now be more particularly described with reference to the accompanying drawings and pointed out in the claims.

Fig. 1 is a perspective view of a container filling and sealing machine embodying the invention;

Fig. 2 is a plan view of the machine shown in Fig. 1; Fig. 3 is a right side elevation, partly in section, of the machine shown in Fig. 1;

Fig. 4 is a plan view, partly in section, of portions of the filling apparatus;

Fig. 5 is a rear elevation of the filling apparatus shown in Fig. 4;

Fig. 6 is a sectional view taken on the line VI—VI of Fig. 4;

Fig. 7 is a plan view of a portion of the cap positioning mechanism;

Fig. 8 is a side elevation of the cap positioning mechanism shown in Fig. 7;

Fig. 9 is a rear elevation of the cap positioning mechanism shown in Figs. 7 and 8;

Fig. 10 is a sectional view of the cap sealing mechanism taken along the line X—X of Fig. 2;

Figs. 11, 12 and 13 are detail views of the container ejecting mechanism;

Fig. 14 is a plan view of the main portions of the driving mechanism;

Fig. 15 is a plan view with parts broken away of the intermittent drive mechanism for rotating the turret; and

Fig. 16 is a section view of portions of the drive mechanism on the line XVI—XVI of Fig. 15.

Referring to Figs. 2 and 3, the illustrative machine comprises a main frame 2 having a lower enclosed compartment 4 in which are located all of the driving instrumentalities. The compartment 4 is completely closed in order that the driving instrumentalities will be protected when the operating portions of the machine are cleaned, as for example, by pressurized steam. A table 6 of non-corrosive material such as stainless steel, separates the various operating instrumentalities, from the driving instrumentalities within the compartment 4.

For supporting the individual unit containers and transporting them to the various work stations comprising the operating instrumentalities is a turret 8. Formed in the turret are a plurality of container receiving cavities 10, each of which is lined with an annular insulating member 12 of glass or other ceramic material having an interior diameter sufficient to accommodate the body portion of the container. An upper surface 14 of the insulator (Fig. 10) supports the flange of the container. Contiguous with the cavities 10 are counterbored channels 16 to accommodate projecting pull tabs of the container covers should they be so constructed. The turret 8 is secured to a hub 18 which in turn is keyed to a driving shaft 20. The shaft 20 is driven from an intermittent drive mechanism 22 which will be described in more detail hereinafter.

Empty containers are moved from a loading table 23 by an operator and positioned in the cavities 10 in the turret 8. The containers are indexed intermittently in a clockwise direction as viewed in Figs. 1 and 2 to a filling station or filler 24 which deposits a predetermined quantity of material in each container. The illustrated machine is designed to fill the containers with a liquid material from a pipe 25 which, as seen in Fig. 3, is constructed with sharp angular bends to reduce the possibility of dripping to a minimum. Any overflow of material passes into a collecting cup 26 (Fig. 3) in the table 6 and thence to a removable tray 28 within the compartment 4.

The filler 24, best seen in Figs. 4, 5 and 6, comprises a conical reservoir 30 mounted on a main body or cylinder housing 32. Rotatable within the body 32 is a valve 34 having a first passageway 36 extending diametrically through the valve and a second passageway 38 extending radially intersecting the passageway 36 at an angle of 90°. A longitudinally extending cylinder 40 communicates with the valve 34 and slidably within the cylinder is a piston 42 from which extends a piston rod 44. The valve 34 is rotated between a first or intake position wherein the passageway 36 is in alignment with a vertical passageway 46 communicating with the reservoir 30. In this position the passageway 38 is in communication with the cylinder 40. In the second or discharge position, 90° from the first position and as shown in Fig. 6, the passageway 38 is blocked and the passageway 36 communicates with a horizontal passageway 48 leading to the filler pipe 25. Adjustably connected to the piston rod 44 by a threaded link 50 and adjusting nuts 51 is a fluid motor or hydraulic cylinder 52, of conventional design, such as that known as an Airoyal Cylinder, H-series. Connected to the rotary valve 34 by a crank 54 and an adjusting rod 56 is another fluid motor 58 of like design. The motors 52 and 58 are single acting, each having a return stroke controlled by an appropriate spring (not shown).

Rotation of the valve 34 and the reciprocation of the piston 42 take place in synchronism under the control of their respective fluid motors, whereby when the valve 34 is in its intake position the piston 42 is moved to the right thereby drawing fluid from the reservoir into the cylinder 40 and when the valve 34 is moved to the discharge position, as seen in Fig. 6, the piston 42 is moved toward the left thereby forcing the fluid from the cylinder 40 into the discharge pipe 25. The stroke of the piston 42 is determined by rotation of the link 50 and the adjusting nuts 51 whereby the quantity of fluid deposited in each container may be accurately controlled.

From the filling station 24 the containers are moved by the turret to the cap or cover positioning mechanism 53, best seen in detail in Figs. 7 through 9. A stack of covers 62 are held in a magazine 64 comprising a plurality of spaced rods 66 mounted in an apertured plate 68. Fitted in the bottom of the plate 68 are a plurality of inwardly extending fingers 70 to keep the covers from falling out of the magazine but of sufficiently small size as not to impede the removal of covers from the magazine. The plate 68 is secured between arms 72, the opposite ends of which are pivoted on fulcrum pins 74 fitted in a bracket 76 which in turn is secured by screws 78 to a main body portion 80 of the cap positioning mechanism. Mounted on a cross plate 82 bridging the arms 72 is a fluid motor 84. A piston rod 86 projects from the fluid motor 84 through a bore 87 in the plate 82 and adjustably mounts on its lower end a pivot bearing 88. The bearing 88 engages an upper horizontal surface 90 of the main body portion 80 of the positioning mechanism. The magazine, and consequently the covers contained therein, are oscillated about the fulcrum 74 through an arc of an acute angle when the pivot bearing 88 alternately is extended from and retracted toward the main body of the fluid motor 84.

The bottommost cover is picked from the magazine 64 by a vacuum picker 94. Fitted in the lower flanged end of the picker is a disk 96 of rubber, or the like, having a plurality of holes 98 communicating with a passageway 100 in the picker 94. The picker is pinned to the end of a horizontal shaft 102 which is journaled in bearings 104, 106 in the member 80. Extending axially through the shaft 102 is a bore 108 communicating with the passageway 100 in the picker. An air hose 110 is attached to the shaft 102 and communicates with the bore 108 which alternately evacuates and pressurizes the passageways 98 in the rubber disk 96 by means hereinafter to be described. Secured to the shaft 102 is a pinion 112 engageable with a rack 114 which is horizontally reciprocated in a guideway 115 by a fluid motor 116. The motor is mounted on a bracket 118 attached to the member 80 and is adjustably connected to the rack 114 by an adjustable bifurcated link 120.

The cover picking and positioning means operates in the following manner. The magazine 64 is elevated by the fluid motor 84 pivoting the arms 72 upwardly about the fulcrum 74. Simultaneously therewith, the fluid motor 116, through the rack and pinion 114 and 112, rotates the picker 94 from the normal or Fig. 8 position wherein the picker rests against an adjustable stop 122 in a mounting plate 123, through 180° or until the picker engages a second adjustable stop 124 wherein the rubber disk 96 faces upwardly and is positioned directly below the magazine 64. The magazine is then permitted to

descend upon the picker disk 96. The passageways 98 are supplied with negative pressure or vacuum via the line 110 and the passageways 109 and 108. The magazine is again elevated slightly whereby the lowermost cover is removed by the picker which then is rotated again into the normal or Fig. 8 position directly above and facing the filled container in the turret 8. The vacuum is then turned off and replaced by a slight jet of air forcibly to eject the cover from engagement with the disk 96 and to position it in engagement with the container flange.

After the cover is placed on top of the container, the turret is indexed to locate the container and its cover C directly beneath a heat sealing element 129, seen best in Fig. 10. This element comprises a hollow pressure applying head 130 which has secured to its lower end an inverted annular recessed disk 132. The disk is engageable with the cover of the container in a ring directly above the flange. An annular heater element 134 is positioned within the head 130 and is connected electrically in series with a thermostat 136, electrical power being supplied thereto through wires 138 from any appropriate source (not shown). Vertical reciprocating motion is supplied to the pressure applying head by a fluid motor 140 which is connected to the head by a piston rod 142, a boss 144 and a ceramic insulator 146, the latter being secured to the head 130 by screws 148 (only one of which is shown). The fluid motor 140 is mounted on a bracket 150 secured to the top of a cylinder 152. The heater element conductor wires 138 and various hydraulic fluid lines while not shown in the drawings pass through the interior of the cylinder 152 gaining entrance thereto through appropriate openings 154 and 156 and thence into the compartment 4 through an opening 158 in the table 6. After the container has been positioned beneath the pressure applying head 130, the head is forced downwardly, the heated annular disk 132 forcing the cover against the flange of the container whereupon the vinyl to vinyl surfaces fuse, forming a hermetic seal between the cover and the flange. Added rigidity is afforded the turret 8 during this process by a support 160 secured to the table 6 beneath the head 130.

When the cap has been sealed to the container, the head 130 is retracted upwardly and the turret is indexed to the next station where the filled and sealed container is removed from the turret. An ejector 169, best seen in Fig. 11, comprises a substantially cylindrical pusher 170 secured to an arm 172 which is clamped to a piston 174 projecting upwardly through the table 6 and a rod 175. A fluid motor 176 clamped to the undersurface of the table 6 moves the rod 175. The piston 174 slides within a sleeve 177 in order to prevent dirt and/or moisture from descending into the compartment 4 with the arm 172 projecting from a slot 178 formed in the sleeve. When the turret is indexed to a position wherein the container is directly above the pusher 170, the fluid motor 176 raises the pusher 170 which ejects the container from the turret. After being ejected, the container is displaced onto a downwardly extending chute 180 by a sweeper arm 182. The arm is secured to the upper end of a shaft 184 journaled within a protective tube 186. Oscillating motion is imparted to the shaft by a fluid motor 188 mounted below the table 6 and connected by a bifurcated link 190 to an arm 192 which is pinned to the lower end of the shaft 184. Return motion of the sweeper arm 182 is effected by a tension spring 194. Movement of the arm is limited by an adjustable stop member 196 (Fig. 2).

All of the operating instrumentalities including the filler, the cover positioning mechanism, the sealer and the removing mechanism, etc., are operated from driving mechanism within the compartment 4. An electric motor 200 (Fig. 14) through a speed reducer 202 and gears 204, 206 rotates a main drive shaft 208. The shaft is journaled in pillow blocks 210, 212. A bank of cams A, B, C, D, E, F and G are secured to the shaft 208.

Each cam supplies driving motion to a corresponding hydraulic master cylinder a, b, c, d, e, f and g through similar cam follower mechanism. Only one cam G, and its follower mechanism, will be described. Referring to Fig. 3, the cam is split and clamped to the shaft 208 by screws (not shown) to permit it to be rotated in order to adjust timing. A cam follower 216, engageable with the cam, is pivoted on an arm 218 fulcrumed in a bracket 220 on the base of the machine. The arm 218 is pivotally connected by a bifurcated link 222 to an extending piston rod 224 of the master cylinder g. In like manner each of the other cams are connected to their master cylinders. In turn each of the master cylinders is connected to one of the fluid motors for operating: the filler, the cap positioner, the pressure applying head, the ejector and the sweeper arm, etc. Each of the fluid motors is of the single acting type similar to the hydraulic brake cylinder of an automobile and accordingly requires a spring for its return movement. In most instances, the springs are not shown in the drawings.

The vacuum and the pressure for the cover picker 94 is obtained from a double acting air cylinder 226 (Fig. 3) one end of which is pivotally secured to the machine frame. Projecting from the cylinder 226 is a piston rod 228 which is pivotally connected to an arm 230 which is reciprocated about a fulcrum 232 by a cam 234 (Fig. 14) engageable with a cam follower 236 pivoted on the arm 230. The cam 234 is, as are all the other cams, mounted on the main drive shaft 208. Since the air cylinder 226 is double acting, movement of the piston rod 228 in one direction produces a vacuum and, in the opposite direction, a flow of air through the line 110 which leads to the picker 94.

The indexing motion of the turret is derived from the above-mentioned intermittent drive mechanism 22. The shaft 20 to which the turret 8 is secured is journaled in bearings 240, 242 (Fig. 16) and has keyed to its lower end a gear 244. Meshing with the gear 244 and secured to a shaft 246 is a pinion 248. A Geneva or star wheel 250 is secured to the pinion 248 and receives its power from a conventional Geneva driver comprising a roll 252 arranged to enter slots 253 in the star wheel. The roll is pivoted on the end of a driver arm 254 which in turn is secured to an input shaft 256. The shaft 256 is driven through a pair of beveled gears 258, 260, the latter being secured to a horizontally extending shaft 262 journaled in brackets 264, 266.

In order to avoid spilling the contents of the containers at the beginning and end of each increment of indexing motion where, respectively, the acceleration and deceleration are the greatest, and without slowing down the over-all cyclic time of the turret, the motion of the Geneva driver shaft 256 is modified. This shaft is driven in such manner that its angular velocity is sinusoidal with the lowest point of velocity occurring each time the Geneva driver roll 252 has fully penetrated a slot 253 in the Geneva star wheel 251 and is about to begin to be withdrawn. Accordingly, the driver roll 252 is decelerating when it enters the slot and is accelerating when it leaves the slot. This, of course, being opposite to the normal starting acceleration and stopping deceleration of a Geneva star wheel, tends partially to reduce these undesirable conditions resulting in an elimination of spilling.

Sinusoidal angular velocity is imparted to the horizontal shaft 262 and, consequently to the Geneva driver, by an endless chain 270 which passes around a concentric sprocket wheel 272 (Fig. 3). The chain is driven from an eccentric sprocket wheel 274 mounted on the cam shaft 208 and having teeth equal in number to those of the concentric sprocket wheel 272. An idler sprocket wheel 276 journaled in a spring-biased arm 278 likewise engages the chain 270. The cam shaft 208 and, consequently the eccentric sprocket 274, are driven at constant angular velocity. However, intermittent or

sinusoidal linear velocity is imparted to the chain 270 because of the different peripheral velocities of the teeth on the eccentric sprocket 274 engaging the chain. The sinusoidal linear velocity of the chain is translated directly into sinusoidal angular velocity of the shaft 262 since the sprocket wheel 272 is concentric with the shaft. Slack in the chain 270 is taken up by the spring-biased idler sprocket wheel 276.

Having thus described my invention, what I claim as new and desire to secure by Letters Patent of the United States is:

1. In a machine for filling and sealing containers, a turret having a plurality of cavities formed to receive containers, means for filling a container, means for positioning a cover on the container comprising a pneumatically operated picker having a cover engaging surface, a magazine for holding a stack of covers above said picker, means for rotating the picker about a first horizontal axis from a position where the engaging surface faces the bottommost cover in the magazine to a position where it faces toward a container in the turret, means for pivoting the magazine about a second horizontal axis normal to said first axis toward and away from the picker, means for correlating the movement of the picker and the magazine whereby the magazine moves toward the picker when the picker faces toward the bottommost cover, fluid pressure means associated with the picker for removing the bottommost cover from the magazine by vacuum and depositing it on the container, means for forming a hermetic seal between the cover and the container, and means for removing containers from the turret after they have been filled and sealed.

2. In a machine for filling and sealing containers, a turret having a plurality of cavities formed to receive containers, operating elements comprising means for filling a container, means for positioning a cover on the container, means for forming a hermetic seal between the cover and the container and means for removing containers from the turret after they have been filled and sealed, means for driving each of said operating elements comprising a fluid motor associated therewith, a master cylinder hydraulically connected to each of said fluid motors, a cam shaft, and a plurality of cams on said shaft, each cam being associated with one master cylinder for imparting an operating stroke thereto, said driving means being contained within a compartment separate from said operating instrumentalities.

3. In a machine for filling and sealing containers, a plurality of work stations comprising means for filling a container, means for positioning a cover on the container and means for sealing the cover to the container, a turret for conveying containers to said work stations, means for indexing said turret intermittently comprising a Geneva drive mechanism, and means for delivering sinusoidal input to said Geneva mechanism to reduce acceleration and deceleration at the beginning and end of each indexing movement thereby to eliminate spilling the contents of the filled containers.

4. In a machine for filling and sealing containers, a plurality of work stations comprising means for filling a container, means for positioning a cover on the container and means for sealing the cover to the container, a turret for conveying containers to said work stations, means for indexing said turret intermittently comprising a Geneva drive mechanism, means for delivering sinusoidal input to said Geneva mechanism to reduce acceleration and deceleration at the beginning and end of each indexing movement thereby to eliminate spilling the contents of the filled containers comprising a driving shaft, a driven shaft connected to said Geneva mechanism, an eccentric sprocket on said driving shaft, a concentric sprocket on said driven shaft, an endless chain connecting said sprockets, and means for taking up slack in said chain.

5. In a machine for filling and sealing containers, a

15 turre^t having a plurality of cavities formed to receive containers, means for filling a container, means for positioning a cover on the container comprising a pneumatically operated picker having a cover engaging surface, 5 a magazine for holding a stack of covers above said picker, means for rotating the picker from a position where the engaging surface faces the bottommost cover in the magazine to a position where it faces toward a container in the turret, means for moving the magazine toward and away from the picker to present the bottommost cover to the picker and fluid pressure means associated with the picker for removing the bottommost cover from the magazine by vacuum and depositing it on the 10 container, means for forming a hermetic seal between the cover and the container, and means for removing containers from the turret after they have been filled and sealed, the means for rotating the picker and for moving the magazine comprising separate fluid motors controlled 15 from a single control mechanism.

20 from a single control mechanism.

6. In a machine for filling and sealing containers, a
turret having a plurality of cavities formed to receive
containers, operating elements comprising means for fill-
ing a container, means for positioning a cover on the
container, means for forming a hermetic seal between
25 the cover and the container and means for removing
containers from the turret after they have been filled
and sealed, means for driving each of said operating
elements comprising a fluid motor associated therewith,
a master cylinder hydraulically connected to each of said
30 fluid motors, a cam shaft, and a plurality of cams on
said shaft, each cam being associated with one master
cylinder for imparting an operating stroke thereto, said
driving means being contained within a compartment
separate from said operating instrumentalities, means for
35 indexing said turret intermittently comprising a Geneva
drive mechanism, and means for delivering sinusoidal
input to said Geneva mechanism to reduce acceleration
and deceleration at the beginning and end of each index-
ing movement thereby to eliminate spilling the contents
40 of the filled containers.

45 7. In a container filling and capping machine, a cover
magazine, means for supporting a filled container to be
capped directly below said magazine, means for trans-
ferring the bottommost cover in said magazine onto the
45 container, said means comprising a cover picking and
positioning means having a cover engaging member,
means mounting said cover picking and positioning
means for rotation about a fixed horizontal axis, means
for moving said cover picking and positioning means
50 about said axis between a delivery position in which the
cover engaging member is located directly over a con-
tainer on the supporting means and a receiving position
spaced 180° therefrom, and means for moving the maga-
55 zine substantially vertically toward and away from the
cover engaging member in timed relation to the move-
ment of the cover picking and positioning means whereby
the magazine is moved out of the path of the cover
picking and positioning means to permit movement of
55 said means into and out of the receiving position and is
60 moved toward the cover picking and positioning means
when said means is in the receiving position.

8. In a container filling and capping machine, a cover magazine, means for supporting a filled container to be capped directly below said magazine, means for transferring the bottommost cover in said magazine onto the container, said means comprising a cover picking and positioning means having a cover engaging member, means mounting said cover picking and positioning means for rotation about a fixed horizontal axis, means 65 for moving said cover picking and positioning means about said axis between a delivery position in which the cover engaging member is located directly over a container on the supporting means and a receiving position spaced 180° therefrom, means for moving the magazine 70 75

substantially vertically toward and away from the cover engaging member in timed relation to the movement of the cover picking and positioning means whereby the magazine is moved out of the path of the cover picking and positioning means to permit movement of said means into and out of the receiving position and is moved toward the cover picking and positioning means when said means is in the receiving position, and means operative in timed relation to the movement of the cover picking and positioning means for causing a reduction in 10 pressure at the cover engaging member when in receiving position and for producing a blast of air therethrough when in delivering position.
